ARTIFICIAL LIMB

Starlin B. Samons, Sr., River Rouge, Mich.

Application May 17, 1946, Serial No. 671,162

4 Claims. (Cl. 3-5)

1

This invention relates to artificial limbs, and more particularly to an artificial foot and leg together with certain means interconnecting the two to more nearly simulate the human foot and leg.

Heretofore in artificial limbs of this type there is usually a pivotal connection between the leg and foot, and in most instances the relative movements have been limited to forward and rearward movements only.

It is the primary object of this invention to provide an artificial foot and leg combination together with interconnecting means between the two members to permit relative universal movements thereof to function similarly to the human ankle.

It is the further object of this invention to provide a variable spaced relation between the artificial foot and leg members at all times, together with resilient cushioning means interposed therebetween for maintaining said spaced relation.

These and other objects will be seen from the following specification and claims in connection with the appended drawing in which:

Figure 1 is an elevational section of the artificial foot and leg, with the latter fragmentarily shown; and

Figure 2 is a similar broken away and sectioned view thereof indicating the relation of the members when in use on the individual.

It will be understood that the above drawing illustrates merely one preferable embodiment of the invention, and that other embodiments are contemplated within the scope of the claims hereinafter set out.

Referring to the drawing, the artificial leg is fragmentarily shown in Figure 1 with a solid preferably wooden block or base portion 11 and an upright hollow portion 12 forming a part thereof. It is contemplated that leg 11, 12 may be constructed of plastic, aluminum or any other suitable substance.

Said base has a pair of longitudinally arranged slots 13 and 14 which project thereinto from its under surface. The forward portion of base 11 is upwardly inclined at 15 and is normally and inoperatively in spaced relation to a similarly inclined portion 16 forming a part of the resilient rubber bumper 17 suitably secured to the forward portion of foot 18.

The latter also preferably constructed of wood is in the shape of a human foot and has formed in its upper surface a pair of longitudinally arranged slots 19 and 20 which are respectively aligned with corresponding slots 13 and 14.

Substantially vertical opening 21 in leg 11 terminates centrally within slot 14 therein, and is aligned with corresponding substantially ver-

2

tical opening 22 in foot 18, which terminates in slot 20 therein.

Secondary inclined opening 23 formed within leg base 11 centrally terminates in slot 13 therein and is aligned with the corresponding inclined opening 24 in foot 18 which terminates in the slot 19.

It will be noted that slots 13, 14, 19 and 20, as well as openings 21, 22, 23 and 24 are preferably of circular cross section.

Foot 18 has a flexible toe portion 25 preferably of rubber which is normally formed by moulding within a suitable die wherein the rubber when hardened takes the shape of the toe element 25. Furthermore a continuous rubber coating 26 is moulded over the entire foot as illustrated in Figure 1.

A trench or undercut curved slot 27 is formed within the central undersurface portion of the foot extending from the heel thereof and projecting forwardly. The slot is preferably three-quarters of an inch wide and approximately one-half inch deep, and therefore takes up only a small portion of the rear undersurface of the foot.

A similarly curved anchor plate 28 snugly projects and is nested within slot 27 and immovably secured therein by the two screws 29 as shown in Figure 1. Similarly a second preferably aluminum plate 30 is positioned within the hollow portion 12 of the leg, mounted upon the top of base 11 and secured thereon by screw 31.

The square shoulders 32 of bolts 33 project up through square openings in bottom plate 28 and are thus non-rotatively positioned therein. Said bolts project upwardly and loosely through openings 22 and 24 in foot 18, through corresponding openings in preferably rubber cylinders 34, and loosely through the openings 21 and 23 in leg member 11.

The upper ends of bolts 33 project through openings in top plate 30 and through corresponding openings formed in rubber cylinders 35 which bear upon plate 30.

Washers 36 are mounted on bolts 33, and are compressively retained in position by nuts 37 which are threaded on the upper ends of said bolts and which operatively bear upon said washers to cooperatively and compressively engage the top portions of rubber cylinders 35.

The lower ends of resilient cylinders 34 project into and are seated within slots 19 and 20 in foot 18, while their upper ends project into and bear against the inner end portions of the slots 13 and 14 in leg member 11.

Cylinders 34 are of sufficient length and strength as to maintain a substantial spaced relation between foot 18 and leg portion 11. Said cylinders are of sufficient strength as to yieldingly and resiliently support leg member 11 in

spaced relation to foot 18 even when under the compressive weight of the wearer as illustrated in Figure 2.

The forward inclined portion 15 is normally in spaced relation to bumper cushion 17 on foot 18; however in walking with cylinders 34 compressed it is seen that said inclined portion now cooperatively bears upon the corresponding inclined surface 16 of bumper 17.

Bolts 33 being undersize with respect to openings 21, 22, 23 and 24, a definite spaced relation exists therebetween permitting universal tipping movements of members 11 and 18 with respect to each other. This relationship and action between the leg and the foot is almost the same as in the human foot as it is seen that with the foot flat on the ground the leg may be freely tipped into any relative angular position relative to said foot. And conversely said artificial foot may be tipped into any angular position relative to said artificial leg.

A rawhide covering 38 is provided for the outer portion of leg 11, 12 to give strength thereto. The hollow upper portion of leg 11, 12 not shown is constructed and formed to fit the human amputated leg.

A horsehide covering or sock 39 covers the entire foot including slot 27 in its undersurface. Sock 39 projects upwardly, bridges the gap between the lower leg portion 11 and foot 18 and extends upwardly to the point shown in Figure 1. Thus the space between the leg and foot is closed and sealed from the atmosphere and from outside moisture.

The foot and leg are initially adjusted to each other relatively by tightening nuts 37 on bolts 33 so that cylinders 34 are partially compressed. Likewise short cylinders 35 are under a moderate compression which is desirable. Cylinders 35 may thus take up the slack on bolt 33 as leg 11 moves downwardly towards foot 18 in taking a step or when the user's weight is upon that leg. Cylinders 35 are thus adapted to straighten out and expand eliminating lost motion from bolts 33 relative to said cylinders and to the leg portions.

During walking bolts 33 are relatively movable within their openings 21, 22, 23 and 24, axially and transversely permitting relative universal movement between the leg and foot to provide almost perfect ankle motion giving the flexible feeling of the human leg when in use.

It is understood that cylinders 34 constantly maintain a varying spaced relation between the foot and leg members thereby minimizing the shock of the pavement and its transmission to the artificial leg. In other words a yielding cushion is provided for the artificial leg.

Having described my invention, reference should now be had to the claims which follow for determining the scope thereof.

I claim:

1. In an artificial leg, a leg portion, with a pair of spaced slots in its under surface, a foot portion with a corresponding pair of slots in its top surface, resilient cushions interposed between said portions with their ends retainingly nested in said slots to maintain a varying spaced relation between said portions, and securing bolts extending through said cushions and loosely through corresponding openings in said leg and foot portions interconnecting the same and permitting universal tipping motion of one portion relative to the other.

2. In an artificial leg, a leg portion, with a pair of longitudinally spaced slots in its under surface, a foot portion with a corresponding pair of slots in its top surface, resilient means interposed between said portions with their respective ends retainingly nested in said slots to maintain a varying spaced relation between said portions, securing bolts extending upwardly from the under side of said foot portion, through said resilient means and loosely through corresponding openings in said leg and foot portions interconnecting the same and permitting universal tipping motion of one portion relative to the other, one of said portions being axially movable relative to said bolts upon relative movement of one of said portions toward the other, and normally compressed resilient means interposed between said movable portion and said bolts to expansively take up the slack therebetween.

3. In an artificial leg, a leg portion with a plurality of longitudinally spaced slots in its under surface, a foot portion with corresponding slots in its top surface, rubber cylinders interposed between said portions with their ends retainingly nested in said slots to maintain a varying spaced relation between said portions, and a plurality of bolts secured to and extending upwardly from the bottom of said foot portion, through said cylinders and loosely through corresponding coaxial openings in said leg and foot portions, being also secured to said leg portion to adjustably interconnect said portions and to permit universal tipping movement of one portion relative to the other.

4. In an artificial leg, a leg portion with a plurality of longitudinally spaced slots in its under surface, a foot portion with corresponding slots in its top surface, rubber cylinders interposed between said portions with their ends retainingly nested in said slots to maintain a varying spaced relation between said portions, a plurality of bolts secured to and extending upwardly from the bottom of said foot portion, through said cylinders and loosely through corresponding coaxial openings in said leg and foot portions, being also secured to said leg portions to adjustably interconnect said portions and to permit universal tipping movement of one portion relative to the other, and normally compressed rubber cylinders loosely mounted and secured upon the upper ends of said bolts and bearing against said leg portion and adapted to expansively take up the slack between said bolts and leg portion upon downward compressive movement of the latter relative to said bolts.
